(57) **CLAIM**

The ornamental design for a fitness weight stand, as shown and described.

DESCRIPTION

FIG. 1 is a top front right side isometric view with environment of a fitness weight stand showing my new design; FIG. 2 is a top front right side isometric view without environment of the fitness weight stand of FIG. 1; FIG. 3 is a bottom rear left side isometric view of FIG. 2; FIG. 4 is a front elevation view of FIG. 2; FIG. 5 is a rear elevation view of FIG. 2; FIG. 6 is a left side elevation view of FIG. 2; FIG. 7 is a right side elevation view of FIG. 2; FIG. 8 is a top plan view of FIG. 2; and, FIG. 9 is a bottom plan view of FIG. 2. The broken lines in the drawings depict portions of the fitness weight stand that form no part of the claimed design.
